Primary Examiner — Lilyana Bekic*(74) Attorney, Agent, or Firm* — Steven J. Schwarz(57) **CLAIM**

The ornamental design for an intranasal drug delivery device, as shown and described.

DESCRIPTION

FIG. 1 is a top perspective view of an intranasal drug delivery device, showing our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top planfront elevation view thereof.

FIG. 7 is a bottom plan view thereof; and,

FIG. 8 is a bottom perspective view thereof.

The features shown in broken lines represent portions of the intranasal drug delivery device which form no part of the claimed design.

1 Claim, 7 Drawing Sheets(56)
